UNITED STATES PATENT OFFICE.

ALOIS LEISTLER, OF HOLLENSTEIN, YBBS, AUSTRIA-HUNGARY.

AUTOMATICALLY-LOCKING LOCK.

1,142,591.

Specification of Letters Patent.

Patented June 8, 1915.

Application filed March 9, 1914. Serial No. 823,612.

To all whom it may concern:

Be it known that I, ALOIS LEISTLER, land-owner, a subject of the Emperor of Austria-Hungary, and residing at Hollenstein, 5 Ybbs, Lower Austria, in the Empire of Austria-Hungary, have invented certain new and useful Improvements in Automatically-Locking Locks, of which the following is a specification.

10 A primary object of this invention is to provide an improved automatically locking lock for drawers, doors and the like of that type in which the bolt, which is normally held in its unlocked position, is released directly or indirectly by means of a blow 15 on an auxiliary member from the latter. In locks of this type as at present known the auxiliary member projects from the case of the lock and this has the disadvantage that 20 when the drawer or door is open, the bolt may be released by accidental contact with the auxiliary member, so that the bolt must be pushed back by means of the key before the drawer or door can be shut. In the 25 improved lock forming the subject matter of my invention I obviate this defect by arranging the auxiliary member completely inside the lock-case and providing the latter with an aperture through which a stop, pro- 30 vided on the guide of the drawer or on the frame of the door, enters when the drawer or door is closed and actuates the auxiliary member. This advantage is of importance particularly for locks on drawers, because 35 when manipulating with the contents of the drawer it may readily happen that owing to a portion of the contents striking the auxiliary member the bolt is released.

Several embodiments of my invention are 40 represented by way of example in the accompanying drawings, wherein:

Figure 1 is a front elevation of a lock particularly intended for drawers, the cover-plate having been removed and the lock being shown in its unlocked position; the auxiliary member is located inside the case of the lock and itself holds the bolt in its unlocked position; Fig. 2 is a cross section taken on the line A—A in Fig. 1, and Figs. 45 3 and 4 are like views, respectively, of the lock in its locked position; Fig. 5 is a view corresponding to Fig. 1, showing a lock differing from that shown in this figure in that the auxiliary member acts on tumblers; Fig. 6 is a horizontal section taken on the 50 line B—B in Fig. 5, and Fig. 7 is a like

section of the lock in its locked position; Fig. 8 shows a preferred form of the stop; and Fig. 9 is a horizontal section showing the lock represented in Figs. 1 to 5 when 55 employed on a door.

Referring firstly to Figs. 1 to 4, this lock comprises a bolt 1 which can be moved by means of a key and has a one-step movement. The bolt lies flat on the rear wall 2 of the case of the lock and when moved is guided by a pin 4 projecting through a slot 3. In the locked position the bolt is held by tumblers 5, while it is held in its unlocked position by the auxiliary member 10. The tumblers which are rotatable about the pivot 6 and have a T-shaped recess 7, are held 60 pressed by springs 8 against the stop pin 9 of the bolt. The releasing member or lever 10, disposed adjacent to and parallel with the bolt, is mounted to rock about a pivot 11, mounted on the rear wall 2 and is normally pressed against this wall by a spring 12. This lever 10 is formed as a hook which in the unlocked position of the bolt 1 takes 65 over a lateral projection 1' of the same and thus holds the bolt in this position (Figs. 1 and 2). In proximity to the upper end of the lever 10 the wall 2 is provided in a novel manner with an aperture 13 through 70 which a stop 14, provided on the bottom of the guide of the drawer, can project and coact with the lever 10 when the drawer is being closed. The stop consists of a hook 75 bent rectangularly preferably stamped out 80 of the material of the sheet-metal plate 15.

When the drawer is being closed the stop 14 projects through the aperture 13 into the case of the lock and forces the lever 10 back 85 against the action of the spring 12, whereby 90 the bolt is released and can fly forward under the action of its spring 16 into the locked position represented in Figs. 3 and 4, in which position it is held by the tumblers 5. On the lock being unlocked and the 95 drawer pulled forward the lever 10, held in its tilted position by the stop 14, is removed 100 from the stop and returned into its normal position, in which it again holds the retracted bolt with its hook.

In the embodiment shown in Figs. 5 to 7 the bolt 1 is held by tumblers both in its unlocked and in its locked position; the lowest or rearmost tumbler 5" (Fig. 5) of the three tumblers holds the bolt in its unlocked 105 position, while the two upper or front tumblers 5 and 5' hold it in its locked position.

In order that the tumbler 5" holding the bolt in its unlocked position, may be released by means of the lever 10, the latter is provided not with a hook, but with a beveled lug 17 which coacts with a projection 18 of the tumbler 5".

When the drawer is being closed and the lever 10 is forced back by the stop 14, the tumbler 5" is rocked by the slanting face 17 of the lever 10 and removed from the pin 9 so that the bolt is released and can fly forward into its locked position. On the drawer being unlocked and pulled out the lever 10 returns to its normal position, in which it releases the tumbler 5" so that the latter can move forward into its locking position and hold the retracted bolt 1.

Obviously, instead of the spring-pressed lever 10 a spring may be provided, it being formed with a hook in the lock shown in Figs. 1 to 4, and provided with a lateral slanting face 17 for coacting with the tumbler 5" in the lock according to Figs. 5 to 7.

With reference to the stop 14, the same is preferably movable so that it does not hinder a filled drawer being opened. For this purpose the stop 14' shown in Fig. 8 is mounted to rock between two lugs 15' of the plate 15 in such a manner that it is prevented by this plate from rocking backward out of its operative position, whereas it can rock freely in the other direction. A spring 20 tends to hold the stop in its operative position. Should the drawer be pulled forward and the contents thereof strike against the hook, the latter will be rocked and can enter through an aperture 21 in the plate 15 into the recess 22 in the guide of the drawer. On the drawer being closed or after the pressure exerted on the stop 14' is removed, the latter springs back into its operative position.

The above described lock can also be employed for doors, particularly for the doors or lids of boxes. For this purpose the lock is mounted in such manner in the inner side of the door 24 (Fig. 9) that the aperture 13 in the wall 2 of the lock is located opposite the stop 14 mounted on the frame 25 of the door so that on the door being closed, the stop can enter into the case of the lock and coact with the lever 10. In this embodiment the stop 14 on the plate 15 for receiving the bolt 1 is a pin, and the aperture 13 in the wall 2 extends into the plate 26, in order to enable the pin to enter into the case of the lock. As the auxiliary member does not project through the case of the lock in the above described locks accidental contact with the same and consequent release of the bolt is

rendered impossible. This result can also be obtained when the auxiliary member does project beyond the case of the lock, if the arrangement is such that the projecting part of the auxiliary member of the mounted lock is out of the path of anything which might accidentally strike it, as when it is located in a chamber or space formed by adjacent parts of the article of furniture or between the furniture and the lock.

What I claim as my invention and desire to secure by Letters Patent is:

1. A safety lock comprising in combination a casing, a key-operated locking-bolt, a spring tending to hold said locking-bolt in its locking position, tumblers coöoperating with said locking bolt, an auxiliary member arranged within the casing and adapted to retain the bolt in its unlocked position, said casing being provided with an aperture, and a trip adapted to enter said aperture upon closing to cause said member to release said bolt from its unlocked position.

2. A safety-lock comprising in combination a casing, a key-operated locking-bolt, a spring tending to hold said bolt in its locking position, tumblers holding the locking-bolt in its unlocked position, an auxiliary member arranged within the casing, said casing being provided with an aperture, a trip adapted to enter said aperture upon closing to move said auxiliary member, and a slanting face on the auxiliary member adapted on movement of the latter to release said tumblers.

3. An automatically locking lock for drawers, doors, or the like, comprising a casing, a locking-bolt, means within said casing to maintain said bolt in its retracted position, said casing having an aperture therein in proximity to said means, and a tripping-device for causing said means to release said bolt; when said drawer is closed, comprising a pivoted arm adapted to enter the aperture of the casing of said lock to disengage said means from said bolt, a pocket in the casing of said drawer in which said arm is pivoted and into which the arm may swing when not in the aperture of the casing of the lock, and means for yieldingly maintaining the free end of said arm in its operative position outside said pocket.

In testimony whereof I have signed my name to this specification in the presence of two subscribing witnesses.

ALOIS LEISTLER.
